UNITED STATES PATENT OFFICE.

EARL LOWE, OF ENGLEFIELD, SASKATCHEWAN, CANADA.

INTERNAL-COMBUSTION ENGINE.

Application filed May 27, 1925, Serial No. 33,234, and in Canada January 8, 1925.

The invention relates to improvements in internal combustion engines and an object of the invention is to provide an engine which will develop considerable power with a minimum of fuel and wherein a firing charge is compressed in a separate working chamber coincident with the compression of a charge of air in an adjacent working chamber and wherein coincident with the firing of the firing charge, a connection is established between the two working chambers to permit of the simultaneous out movement of the two pistons in the two working chambers under the force of the explosion occurring in the one chamber.

With the above more important and other minor objects in view which will become more apparent as the description proceeds, the invention consists essentially in the arrangement and construction of parts herein-after more particularly described, reference being had to the accompanying drawing in which:

Fig. 1 is a side view of the engine.

Fig. 2 is a vertical longitudinal sectional view centrally through the engine.

Fig. 3 is a horizontal sectional view through the engine, the section passing through the exhaust ports thereof.

Fig. 4 is an enlarged detailed vertical sectional view at 4-4 Figure 3.

In the drawing like characters of reference indicate corresponding parts in the several figures.

The base 1, of the engine is subsequently rectangular and carries a horizontally disposed open ended cylinder 2, suitably water jacketed as indicated at 3, the water entering the jacket from a water reservoir 4, located above the engine and herein shown as cast integrally therewith. The cylinder 2 is centrally divided by a head or cross partition 5 which divides the cylinder into two working chambers indicated at 6 and 7. Similar pistons 8 and 9 are slidably mounted in the ends of the cylinder.

One end of the engine base 1 is provided with opposing pedestals 10 and 11 which support rotatably a crank shaft 12, which is provided with a central crank 13 and two side cranks 14 and 15, the crank 13 being positioned 180 degrees from the cranks 14 and 15, and a connecting rod 16 connects the crank 13 with the piston 8 in the usual manner. The piston 9 is provided with a

horizontally extending rod 17, the outer end of which is slidably carried in a bearing 18 located at the upper end of a bracket 19 secured to the engine base. A cross rod 20 is secured to the rod 17 and the ends of the cross rod is connected by connecting rods 21 and 22 to the cranks 14 and 15. Obviously, according to the above arrangement, the pistons will be simultaneously reciprocated in opposite directions in the turning of the crank shaft. The ends of the crank shaft are provided with fly wheels 23 and 24. A magneto 25 of any approved type is mounted on the upper end of the pedestal 11 and a cam shaft 26 is located above the crank shaft 70 and has one end suitably mounted on the upper end of the pedestal 10 and the other passing through the magneto. A two to one ratio is provided between the crank shaft and the cam shaft, the cam shaft being fitted with a gear wheel 27 and the crank shaft with an intermeshing pinion 28. A bypass 29 connects the inner ends of the working chambers, the bypass being formed in the cylinder wall and spanning the partition 80 5. A valve seat 30 is formed in the bypass and a valve 31 normally engages the seat, the valve being provided with an outwardly extending stem 32 suitably guided in a closure plate 33, enclosing the rear side of the bypass. A coil spring 34 holds the said valve normally closed. A cam 35 is secured to the cam shaft and this cam is designed to positively open the valve 31 and hold it open for a predetermined period of time. The 90 cam controls a sliding rod 36, suitably carried by a bracket 37 and the inner end of the rod 36 is connected pivotally to a further rod 38 which is connected to a pivotal bell crank 39 which latter is pivotally attached to the outer end of the valve stem 32. The cam and valve connections are so arranged that the valve is opened coincident with the firing of the charge in the working chamber 6 and the charge is fired by a spark plug 100 40 connected electrically by a wire 41 in the usual manner to the magneto. One side of the magneto and one side of the spark plug is grounded in the usual manner.

At the side of the cylinder remote from the bypass, I locate an inlet port 31 for air and an inlet port 42 for the firing mixture, the port 42 opening to the chamber 6 and that 41 to the chamber 7. A carburetor 43 of any approved design is connected by 110

means of a feed pipe 44 with the port 42 and a spring pressed inlet valve 45 is introduced, this valve opening to admit the charge to the cylinder 6 on the suction stroke of the piston 8 and closing to retain the charge on the compression stroke of the said piston. A similar valve is introduced in the air inlet port 31 but the details of it are not herein shown as it is the same as the latter valve and opens to admit air to the chamber 7 on the suction stroke of the piston 9 and closes on the compression stroke thereof. Directly above the ports 31 and 42, I locate an exhaust port 46 from the chamber 6 and an exhaust port 47 from the chamber 7 and normally closed spring pressed valves 48 and 49 close these ports, the said valves being provided with similar stems 50 which pass slidably through a suitable closure plate 51 provided. The cam shaft is fitted with a further cam 52 similar to that 35 and the said cam 52 engages a sliding rod 53, suitably carried by the bracket 37 and connected to a connecting rod 54 which is pivotally attached to a pivotally mounted bell crank 55. One of the arms of the bell crank engages the outer ends of the valve stems 50 and the cam 52 and parts operating thereby are so arranged that the valves 48 and 49 are simultaneously opened to exhaust the spent charges from the working chambers.

The fly wheel 23 is provided with a governor which is adapted to control a valve 56 in the intake pipe 44, the valve closing as the speed increases and opening on a reduction of speed. The governor comprises two similar diametrically opposing weights 57 and 58, the weights being carried by the horizontal arms of bell cranks 59 and 60, the vertical arms of which turn inwardly towards the crank shaft and are received between a pair of outstanding flanges 61 and 62 carried by a sleeve 63 slidably mounted on the crank shaft. Rods 64 and 65 slidably connect the weights and springs 66 are mounted on the rods to resist the out movement of the weights under the action of centrifugal force.

The engine base carries a pair of bearings 67 and 68 which support rotatably a rod 69, one end of which is fitted with a crank 70, received between the flange 62 and a further flange 71 on the sleeve. The other end of the rod is supplied with a further crank 72 which is connected by an operating bar 73 to the lever 74 of the valve 56. The arrangement of the latter parts is such that the governor will close the valve 56 when the speed becomes excessive and open the same when the speed reduces abnormally.

In order to better understand my invention, I will now describe the manner in which it works assuming that the pistons

are initially in, that is, in a location adjacent the head 5. On the initial simultaneous outstrokes of the pistons, a charge of firing mixture is drawn into the working chamber 6 and an initial charge of air is drawn into the working chamber 7, these charges entering under the suction of the pistons through the ports 42 and 31. The valve 31 is at this time closed. On the subsequent instroke of the pistons, the valves in the ports 31 and 42 automatically close and the valve 31 is held closed by the pressure in the chambers. The firing mixture in the chamber 6 and the air in the chamber 7 are accordingly simultaneously compressed. As the pistons approach their innermost positions, the charge in the chamber 6 is fired by the spark plug and coincident with the firing of the charge, the two chambers are connected by the opening of the valve 31 through the action of the cam 35. The exploded charge in the chamber 6 accordingly is free to pass through the bypass into the chamber 7 and it accordingly acts simultaneously on both pistons to force them out on the working stroke of the engine. During the subsequent instroke of the engine, the cam 52 operates to simultaneously open the valves in the ports 46 and 47 to permit of simultaneous exhaust from the chambers 6 and 7. In the subsequent outstroke of the pistons, a further charge of firing mixture is drawn into the chamber 6 and air is drawn into the chamber 7, and thereafter the cycle is continued in the manner hereinbefore described as long as the engine is running.

What I claim as my invention is:

1. In an internal combustion engine, a divided cylinder providing two separate working chambers, pistons slidably mounted in the working chambers and simultaneously reciprocated in opposite directions, means for admitting a firing charge to one of said working chambers and an air charge to the other of said working chambers on the suction strokes of the pistons, said charges being simultaneously compressed on the compression stroke of the pistons, means for firing the compressed firing charge and means for connecting the chambers coincident with the firing of the charge.

2. In an internal combustion engine, the combination with a centrally divided cylinder providing two working chambers and pistons slidably mounted in said chambers and simultaneously reciprocated in opposite directions therein, of means for admitting a firing charge to one of the chambers and a charge of air to the other of the chambers during the suction strokes of the pistons, said charges being simultaneously compressed on the compression strokes of the pistons, means for firing the compressed

firing charge and means for connecting the chambers coincident with the firing of the latter charge.

3. In an internal combustion engine, the combination with a centrally divided cylinder providing two working chambers and pistons slidably mounted in said chambers and simultaneously reciprocated in opposite directions therein, of means for admitting a firing charge to one of the chambers and a charge of air to the other of the chambers during the suction strokes of the pistons, said charges being simultaneously compressed on the compression strokes of the pistons, mean for firing the compressed firing charge, a bypass connecting the inner ends of the working chambers, a normally closed valve in the bypass controlling the bypass and means for opening the valve coincident with the firing of the compressed firing charge.

4. In an internal combustion engine, the combination with a centrally divided cylinder providing two working chambers and pistons slidably mounted in said chambers and simultaneously reciprocated in opposite directions therein, of means for admitting a firing charge to one of the chambers and a charge of air to the other of the chambers during the suction strokes of the pistons, said charges being simultaneously compressed on the compression strokes of the

pistons, means for firing the compressed firing charge, a bypass connecting the inner ends of the working chambers, a normally closed cam controlled valve inserted in the bypass, said valve being opened by the cam coincident with the firing of the compressed firing charge.

5. In an internal combustion engine, a cylinder divided centrally by a cross partition providing two adjacent working chambers, pistons slidably mounted in the chambers, means for simultaneously reciprocating the pistons in opposite directions, means for admitting a charge of firing mixture to one of the working chambers in the outgoing suction stroke of one of the pistons and for admitting a charge of air to the other of the chambers in the outgoing suction stroke of the other of the pistons, said charges being subsequently compressed on the ingoing strokes of the pistons, a bypass connecting the working chambers and spanning the partition, a normally closed valve inserted in the bypass, means for firing the compressed firing charge and means for automatically opening the valve to connect the chambers coincident with the firing of said latter charge.

Signed at Englefeld, Saskatchewan, this 16th day of May, 1925.

EARL LOWE.
